No. 839,624.

PATENTED DEC. 25, 1906.

J. F. McNEILL.

GO-CART.

APPLICATION FILED NOV. 26, 1905.

UNITED STATES PATENT OFFICE.

JOHN FRANCIS McNEILL, OF MELBOURNE, VICTORIA, AUSTRALIA.

GO-CART.

No. 839,624.

Specification of Letters Patent.

Patented Dec. 25, 1906.

Application filed November 25, 1905. Serial No. 289,105.

To all whom it may concern:

Be it known that I, JOHN FRANCIS McNEILL, a subject of the King of Great Britain, residing at the corner of Spencer and Bourke

5 streets, Melbourne, in the State of Victoria, Commonwealth of Australia, have invented certain new and useful Improvements in Go-Carts and the Like, of which the following is a specification.

10 This invention provides improvements with a view to obviate many of the defects in the existing constructions of go-carts and the like baby-carriages.

In explanation it is mentioned that go-carts

15 as now constructed have rear supporting-legs, the length and normal position of which prevent the elevation of the gutter-wheels sufficiently to surmount curbstones, steps, or other obstacles. With some constructions, in

20 which these legs are fixtures, it is often necessary to turn the go-cart completely round and drag it over the obstacle, while in others, in which these legs are pivotally connected to a part of the go-cart, devices more or less

25 troublesome and inconvenient to operate are provided for raising or swinging the legs out of position when it is required to raise the gutter-wheels to surmount obstacles. Another disadvantage in most constructions

30 of go-carts is that when left unattended to and resting on ground having any slight incline they are apt to move of their own accord, an occurrence often attended with seri-

ous results. By this invention these disad-

35 vantages are removed and an improved go-cart or the like is provided having its supporting-legs so positioned that when in its wheeling or normal position the go-cart may be tilted to any ordinary angle—as, for ex-

40 ample, when passing over high curbstones or steps—without the ends of these legs striking the ground. When, however, it is required to rest the go-cart, simple and effective means are provided by which the go-cart body is low-

45 ered relatively to the main wheels, bringing the supporting-legs into a position that they now contact with the ground and support the go-cart so securely that all possibility of its moving of its own accord is removed. Then

50 by merely elevating the pushing-handles the go-cart body is automatically brought back to its raised or normal position, when the cart may be wheeled either forwardly or rear-

wardly, as may be desired.

55 With these and other objects in view the invention consists of the features of construc-

tion, combination, and arrangement of parts hereinafter fully described and claimed, reference being had to the accompanying drawings, in which—

60 Figure 1 is a side elevation, with parts omitted, of a go-cart in its wheeling or normal position, showing the supporting-legs clear of the ground. Fig. 2 is a side elevation of the same in its "fixed" position, the go-cart body 65 being lowered and the supporting-legs in contact with the ground. Fig. 3 is an elevation in vertical transverse section on line 1 1, Fig. 1. Fig. 4 is an enlarged view of the operating rod or lever in side elevation. Figs. 5 and 6 70 show on an enlarged scale modified forms of the operating rod or lever. Fig. 7 is an enlarged view of a bearing and stop for the axle-bar, and Fig. 8 shows in side elevation the operating rod or lever when used in combination with a swinging axle-bar. 75

In the views the letter A designates the seat or support for the go-cart body, B the main wheels, and B' the gutter-wheels. The main-wheel axle-bar, which in Figs. 1, 2, and 80 3 is shown cranked in order that the go-cart body may be, when desired, conveniently lowered relatively to the main wheels, is marked C.

C' represents any suitable framing for the 85 go-cart, and C² the rear supporting-legs. These legs are fixed, and, as shown in the drawings, they may form part of the go-cart frame.

D is a short operating rod or lever ful- 90 crumed, as by a pivot d, to a supporting-leg or to any other suitable part. This operating rod or lever D is provided at its rear end with a treadle portion, as the foot-latch D', and has axle-connecting 95 means, as indicated by D². Although it may be made in one piece, as illustrated in Fig. 5 of the drawings, said operating-lever in its preferred form consists of two pieces pivotally connected—butt-hinged or otherwise jointed—as at d'.

d² is an overlapping piece or stop firmly keeping in position the two parts of operating-lever D when the go-cart is in its wheeling or normal position.

105 The bearings for the main-wheel axle-bar are marked E and are shown provided with projecting pieces or stops e to prevent the too-far-forward motion of the axle-bar C.

E' represents any suitable spring-supports 110 for the go-cart, and the pushing-handles are marked F.

Referring to Fig. 8, the operating rod or lever D is illustrated in combination with a swinging axle-bar, although for neatness in appearance and effectiveness the cranked axle-bar is preferred. An ordinary axle-bar C is secured by suitable means to a revolute arm C² and when in operation swings as indicated by the dotted line X, while in resuming its normal position the lug or stop e prevents it swinging too far forward. It will thus be seen that when the go-cart is in its raised or wheeling position (illustrated in Fig. 1) the axle-bar is kept in position by the action of the operating-lever D and the stops e, and the go-cart may be tilted to raise the gutter-wheels onto a curbstone or over an obstacle without inconvenience, as the ends of the supporting-legs project but slightly beyond the main-wheel periphery.

When it is required to relieve the pushing-handles of their support or to rest the go-cart on the ground, by depressing the foot-latch D' the lever D exerts a pull on the axle-bar C and releases the same. Then by a downward movement of the pushing-handles F the go-cart body is lowered relatively to the main wheels until the supporting-legs contact with the ground, (illustrated in Fig. 2,) all chance of the go-cart moving of its own accord being thereby removed.

It will be readily understood that the supporting-legs C² may be so positioned that when the go-cart is in its normal position their lower ends do not project at all beyond the main-wheel periphery, and yet by depressing the foot-latch D' said legs are lowered sufficiently to firmly support the go-cart. I find it advisable, however, to so position the legs that in case the pushing-handles are relieved of their support without the lever D being operated the go-cart will not be upset should the weight be thrown from the front to the rear of the go-cart. As will be understood, however, sundry variations and modifications may be made while still retaining the essential features of the invention.

When the go-cart is in its fixed position, by merely elevating the pushing-handles the cart is immediately brought to its normal or wheeling position and may be wheeled either forwardly or rearwardly. The axle-bar and the operating-lever are caused by gravity to resume their normal positions, the go-cart body and the supporting-legs being raised into the position as seen in Fig. 1 of the drawings.

What I claim as my invention, and desire to secure by Letters Patent, is—

1. A go-cart comprising a crank-axle, main wheels journaled upon the crank-axle, a gutter-wheel, a frame secured to the axle

of the gutter-wheel and to the crank-axle, said frame being provided with a supporting-leg, and means by which the crank-axle may be operated to lower or raise the supporting-leg. 65

2. A go-cart comprising a crank-axle, main wheels journaled upon the crank-axle, 70 a gutter-wheel, a frame secured to the axle of the gutter-wheel and to the crank-axle, said frame being provided with a supporting-leg, and means carried by the supporting-leg and connected with the crank-axle and by 75 which said axle may be operated to lower or raise the supporting-leg.

3. A go-cart comprising a crank-axle, main wheels journaled upon the crank-axle, 80 a gutter-wheel, a frame secured to the axle of the gutter-wheel and to the crank-axle, said frame being provided with a supporting-leg, and a pivotally-mounted lever having engagement with the crank-axle and by means of which the axle may be operated to lower or 85 raise the supporting-leg.

4. A go-cart comprising a crank-axle, main wheels journaled upon the crank-axle, a gutter-wheel, a frame secured to the axle of the gutter-wheel and to the crank-axle, 90 said frame being provided with a supporting-leg, and a pivotally-mounted lever having one end connected to the crank-axle and its other end provided with a pedal portion, said lever providing means by which the 95 crank-axle may be operated to lower or raise the supporting-leg.

5. A go-cart comprising a crank-axle, main wheels, journaled upon the crank-axle, a gutter-wheel, a frame secured to the axle 100 of the gutter-wheel and to the crank-axle, said frame being provided with a supporting-leg, and a pivotally-mounted lever having connection with the crank-axle, said lever comprising two sections pivotally connected 105 together and providing means by which the crank-axle may be operated to lower or raise the supporting-leg.

6. A go-cart comprising main wheels, a gutter-wheel, a frame provided with a supporting-leg, said frame being connected to the axle of the gutter-wheel, means by which the frame is connected to the axle of the main wheels, said means being provided with a stop, and means by which the axle 115 may be shifted rearwardly to lower the supporting-leg and shifted forwardly into engagement with said stop to raise the supporting-leg.

In testimony whereof I have hereunto set 120 my hand in presence of two subscribing witnesses.

JOHN FRANCIS McNEILL.
